BRUNO H. SCHMIDT, OF MINNEAPOLIS, MINNESOTA.

CARBURETER.

1,182,714.

Specification of Letters Patent.

Patented May 9, 1916.

Application filed May 22, 1915. Serial No. 29,779.

To all whom it may concern:

Be it known that I, BRUNO H. SCHMIDT, a subject of the Emperor of Germany, and a resident of Minneapolis, in the county of 5 Hennepin and State of Minnesota, have invented a new and Improved Carbureter, of which the following is a full, clear, and exact description.

Among the principal objects which the 10 present invention has in view are: to prevent the congelation of the gasolene, and the sluggishness consequent thereon; to provide a regulator, automatic in character, for increasing the fuel supply for an engine in 15 proportion to the increased speed thereof; to provide means for thoroughly mixing the fuel, the mixture being perfected in proportion to the supply thereof; and to provide means for quickly and readily dismantling 20 the carbureter for repair or cleaning.

Drawings.—Figure 1 is a vertical section on an enlarged scale, of a carbureter constructed and arranged in accordance with the present invention; Fig. 2 is a horizontal section of the same, taken as on the line 2—2 in Fig. 1; Fig. 3 is a horizontal section 25 taken as on the line 3—3 in Fig. 1; Fig. 4 is a detail view of the throttle valve employed in the present invention; Fig. 5 is a detail view showing a fragment of the 30 electric heater employed in the present invention.

Description.—As shown in the drawings, the body of the carbureter has two sections, 35 an upper section 10 and a lower section 11. The sections are provided, the one with an internally-threaded, and the other with an externally-threaded flange. Said threaded flanges, when united, are located midway between the ends of the carbureter. Said 40 flanges also coincide with a spherical mixing chamber 12. When the sections 10 and 11 are parted, the spindle 13, beaters 14, 15 and 16, and valve 17, may be lifted from the 45 section 11 in which they are mainly stowed. A spider 18 in the section 10 serves only as a centering and steadyng member for the spindle 13.

The sections 10 and 11 are both provided 50 with straight outer cylindrical walls and interior cylindrical passages, said passages being formed by the walls 19 and 20, respectively. The wall 19 forms what is herein termed the fuel delivery passage 21, 55 while the wall 20 forms what is herein termed the receiving chamber 22. Between

the walls 19 and 20 and the outer walls of said sections are formed closed chambers 23 and 24, respectively. Both chambers 23 and 24 are provided to heat the gasolene delivered to the carbureter by way of the supply pipe 25, the coil sections 26 and 27, and the float chamber 28. The coil sections 26 and 27 are connected by pipes 29 and 30, which pipes are joined by a union 31. When 60 the coil sections are thus connected, the gasolene is delivered to the chamber 28 without interruption when the free end of the float 32 is lowered to permit the needle valve 33 to open the ingress to said chamber. The 70 float 32 is partly supported by a hinge 34. A portion of the hinge 34 is intimately connected with a screw 35, the manipulation of which serves to adjust the float in the chamber 28 to accommodate a needle valve 33. 75

Extending across the chamber 22, to form an entrance thereto, is a spider having a central body 36, from which upwardly extends a distributing tube 37. The tube 37 has a series of needle orifices 38, through 80 which the oil or gasolene is injected into said chamber 22. The chamber 22 is normally supplied with air through the passages in said spider when the throttle valve 39 is adjusted to place screen-covered openings 40 85 in register with the openings in said spider. When the solid portions of said valve register with said spider, the admission of air to the chamber 22 is discontinued. To manipulate the valve 39, the same is provided 90 with a lever 41.

To heat the gasolene or oil in its passage from the pipe 25 to the chamber 22, there are provided two distinct chambers. The chamber 23 is provided with a hot water 95 inlet pipe 42 and an outlet pipe 43. The pipes 42 and 43 are suitably connected with the water-jacket of the engine with which the carbureter is employed when in service, and the water delivered to the chamber 23 100 by said pipe 42 serves to heat the gasolene or oil as the same passes through the coil section 26. The heat retained by the gasolene when passing through this chamber has been found sufficient to endure until said 105 gasolene or oil has been delivered to the chamber 28 and therefrom to the chamber 22.

The chamber 24 in the section 11, and the coil section 27 mounted therein, are called 110 into service when the hot water is not available, or when the hot water is not sufficient

to heat said gasolene. To heat the coil section 27, the chamber 24 is provided with a series of electrical heaters. The heaters referred to comprise supporting rings 44, 45, 5 46 and 47. The rings 44 and 45 are of relatively large diameter, and are supported upon the outer wall of the section 11 adjacent the upper and lower ends of the chamber 24. Said rings are perforated at 10 suitable intervals to receive a suitable resistance wire 48, which is interwoven between the two rings, much in the manner as shown in Fig. 5 of the drawings. The wire 48 is continuous with a wire 49, which is threaded 15 between the rings 46 and 47, shown best in Fig. 5 of the drawings.

The ends of the wire 48—49 are properly connected by binding posts 50, with a suitable electric source. The source selected 20 should be able to heat the wires 48—49 and thereby raise the temperature within the chamber 24. It will be understood that when the heat of the water in the chamber 23 is sufficient to properly influence the gasolene or oil, the service of the electric heater 25 is discontinued, but when it is found that the heat of the water in the chamber 23 is insufficient for the purpose designed, then the electric heater is employed until the 30 water supplied to the chamber 23 is sufficient for the purpose designed.

As above stated, the oil delivered to the tube 37 is distributed therefrom by way of the orifices 38. The orifices 38 are disposed 35 longitudinally in the tube 37, and are normally closed by the tapered valve 17. The valve 17 is normally seated on a surface formed on the ledge 52 at the upper edge of the chamber 22. In the normal operation 40 of the engine, the lowermost orifice 38 is exposed by the valve 17, which orifice supplies sufficient gasolene to mix with the air in the chamber 22 to form therewith a fuel which passes through apertures 53 in the 45 valve 17, to supply a limited amount of fuel to the mixing chamber 12. Among other advantages which this carburetor has in view is to increase the supply of fuel in correspondence with the consumption of fuel 50 and with the speed of the engine supplied therewith.

As the engine increases its speed, the force of suction of the intake is correspondingly increased. The draft of air passing upward 55 through the chamber 12 operates upon the inclined blades of the beater 16, to rotate the same and the hub block 54 with which they are connected.

The block 54 rests on ball bearings 55, 60 and is provided with hinge extensions 56, to which extensions the arms 57 having weighted balls 58 at the ends thereof, are connected. The arms of the centrifuge thus constructed are connected by rods 59, with 65 a collar 60. The collar 60 is mounted upon

ball bearings between the body of the valve 17 and the cap 61 thereof.

It is obvious that as the passage of air through the chamber 12 increases in speed and force, the balls 58 are spread to lift the collar 60 and valve 17 connected therewith from the seat on the ledge 52 provided for said valve. The valve 17 being thus lifted, the second, third, fourth and fifth orifices are exposed to deliver gasolene from the tube 37 to the chamber 22. The increased volume of air permitted to pass from the chamber 22 is thus assisted by the increased volume of gasolene admitted thereto for admixture with said air. As the speed of the beaters 16 increases coincident with the increased speed of the engine, the valve 17 is lifted to free the delivery of fuel from the chamber 22, and to admit an added quantity of gasolene to said member.

The gasolene and air thus admitted to the chamber 22, and thence to the chamber 12, is thoroughly mixed in passing through said chamber 12, by the operation of the beaters 14, 15 and 13. The beaters are propelled by the current of the fuel passing through said chamber 12, and operate to deflect the same from the straight line. It will be noticed that the blades of the beaters 14 and 16 are pitched in one direction, while the blades of the beater 15 are pitched in the reverse direction. As a concomitant to this construction, the current deflected by the beater 16 to one side, is in turn deflected in an opposite direction by the beater 15, to be again deflected by the blades of the beater 14.

The beaters 14 and 15 are provided with hubs 62 and 63, respectively. The column of beaters 14, 15 and 16 is maintained positioned between a base 64 and a cap 65, said base and cap being flexibly mounted on the stationary spindle 13.

When the fuel, having passed from the chamber 22, reaches the passage 21, it is thoroughly and completely mixed to form an explosive gas having an even and constant quality.

Claims:

1. A carburetor comprising an elongated mixing chamber having double walls spaced apart to form annular unconnected chambers, said chambers forming end compartments; a water supply for one of said compartments, said supply being connected with the circulating system of an engine; an electric heater disposed in the other compartment, said heater being connected with any suitable electric source; means for supplying fuel to said mixing chamber, said means embodying a delivery pipe; and a plurality of coils connected therewith, said coils being one contained within the first-mentioned compartment and the other within the second-mentioned compartment, said coils being operatively engaged to form a con-

tinuous passage for the fuel passing through both of said compartments to said mixing chamber.

2. A carbureter comprising an elongated mixing chamber having double walls spaced apart to form annular unconnected chambers, said chambers forming end compartments; a water supply for one of said compartments, said supply being connected with the circulating system of an engine; a temporary heater for the other of said compartments for use, pending the heating of said water supply; means for supplying fuel to said mixing chamber, said means embodying a delivery pipe; and a plurality of coils connected therewith, said coils being one contained within the first-mentioned compartment and the other within the second-mentioned compartment, said coils being operationally engaged to form a continuous passage for the fuel passing through both of said compartments to said mixing chamber. ²⁰
- 10 the circulating system of an engine; a temporary heater for the other of said compartments for use, pending the heating of said water supply; means for supplying fuel to said mixing chamber, said means embodying
- 15 a delivery pipe; and a plurality of coils con-

nected therewith, said coils being one contained within the first-mentioned compartment and the other within the second-mentioned compartment, said coils being operationally engaged to form a continuous passage for the fuel passing through both of said compartments to said mixing chamber.

In testimony whereof I have signed my name to this specification in the presence of two subscribing witnesses.
